UNITED STATES PATENT OFFICE.

ADOLPH P. GUSTAFSON, OF CHICAGO, ILLINOIS, ASSIGNOR TO M. SCHULZ COMPANY, OF CHICAGO, ILLINOIS, A CORPORATION OF ILLINOIS.

PNEUMATIC ACTION.

1,359,456.

Specification of Letters Patent. Patented Nov. 16, 1920.

Application filed August 13, 1919. Serial No. 317,124.

To all whom it may concern:

Be it known that I, ADOLPH P. GUSTAFSON, a citizen of the United States, residing at Chicago, in the county of Cook and State of Illinois, have invented a certain new and useful Improvement in Pneumatic Actions, of which the following is a full, clear, concise, and exact description, reference being had to the accompanying drawings, forming a part of this specification.

My invention relates to pneumatic actions, and particularly to pneumatic actions for automatic musical instruments, such as piano players, player pianos and the like.

One of the objects of the invention is to provide a practical and effective construction of pneumatic action.

Another object of the invention is to simplify the construction, and thereby reduce the cost of manufacture.

Another object of the invention is to obtain quickness and sensitiveness of operation.

Another object of the invention is to improve the valve mechanism, simplifying the same, securing directness and positiveness of action, and permitting ready assemblage and adjustment.

In the accompanying drawings, Figure 1 is a plan view of a pneumatic action embodying my present invention; and

Fig. 2 is a cross section on line 2—2 in Fig. 1.

In the drawings I show a section or part of a pneumatic action of a player piano, and part of the piano action operated thereby. This involves a series of pneumatics 1, 2 and 3, shown mounted in a row, with their swinging leaves provided with projections or clips 1^a, 2^a, and 3^a, adapted for engaging projections or abutments 4, 5 and 6 on uprights or stickers 7, 8 and 9. The latter form part of the piano action of the instrument, it being understood that said stickers are actuated so as to operate the piano action by the collapse of the pneumatics 1, 2 and 3.

The pneumatics 1, 2 and 3 are secured at intervals along the under side of a wind chest 10, which is understood to be suitably supported in the piano case and extend

from side to side in the same. This wind chest 10 has a longitudinally extending wind chamber 11, in which a condition of reduced air pressure is normally maintained; and in this are located small pneumatics or puppets 12, one for each of the pneumatics 1, 2 and 3. These puppets 12 act upon the upper ends of prongs or projections 13 secured near the ends of swinging valve members or levers 14 attached by screws 15 to the upper side walls of the pneumatics 1, 2 and 3. The projections 13 extend through openings or ports 16 in the top walls of the pneumatics, and these openings or ports 16 are controlled by the adjacent end of the lever 14, a layer 17 of felt or other suitable material being provided on the lever 14 to make a tight joint when the port 16 is closed. Other ports 18 afford communication between the interiors of the pneumatics 1, 2 and 3, and the outside air, and are controlled by the other ends of the levers 14, layers 19 of felt or other material being provided to close ports tightly. Weights 20, conveniently consisting of disks of lead or other metal, are embedded in the ends of levers 14 controlling ports 18, said weights 20 being conveniently arranged underneath felt layers 19.

The valve levers 14 are fitted in grooves 21 in the upper or fixed walls of the pneumatics 1, 2 and 3, the grooves 21 being substantially wider than levers 14, so as to permit free operation of the latter. The screws 15 hold the levers 14 loosely but securely in position, so that said levers are free to swing up and down to open and close the ports 16 and 18. The levers 14 may be adjusted by adjusting the screws 15.

Tracker board tubes 22, one for each pneumatic 1, 2 and 3, are shown connected to the wind chest 10, it being understood that these tubes extend to the tracker board in the usual way. These tubes 22 communicate with ducts or passages 23, extending to the puppets 12. Small chambers 24 are formed at points of connection of tubes 22 and ducts 23 and small metal thimbles 25 providing bleeds 26 are fitted in said chambers 24. Flat disks 27 are desirably fitted

over the chambers 24 to substantially close same and keep out dust and dirt, the disks 27 having small apertures 28 to admit air.

In operation, the parts are normally in the 5 positions shown in Fig. 2. When an aperture in the music sheet passes over the port controlling the pneumatic 3, air is admitted in the tube 22 connected with said port, and passing through the same and duct 23 causes 10 expansion of puppet 12. This latter acts upon the prong 13, thereby depressing the end of lever 14, opening port 16 and closing port 18. The opening of port 16 permits air in pneumatic 3 to be withdrawn 15 into wind chamber 11, thereby collapsing said pneumatic and actuating the piano action sticker 9. When the aforesaid tracker port is closed by end of music sheet aperture, air is shut off from tube 22, permitting same 20 to be collapsed by lever 14, it being understood that weight 20 is sufficiently heavy to swing right hand end of lever 14 upwardly and collapse puppet 12 when same is free to collapse. By this movement the port 16 is 25 closed and port 18 opened, whereby outside air is admitted to interior of pneumatic 3 and same expanded. In this way pneumatic 3 is collapsed and expanded and sticker 9 actuated repeatedly in accordance with perforations in music sheet.

The lever 14 is loosely mounted by the screw 15, so that it can adjust itself automatically to the ports 16 and 18. It is also held in position by being located in the 35 groove 21. Said lever 14 may be adjusted and tightened and loosened by adjusting the screw 15. The various parts are readily accessible with but little disassembly of the structure.

40 It is understood that changes and modifications may be made without departing from the spirit of the invention.

What I claim is:

1. The combination of a power pneumatic 45 having one of its sides provided with air and suction ports, a lever extended between said ports and pivoted between its ends, the ends of said lever serving as valves for said ports, a projection on the end of the lever 50 controlling the suction port and a hinged pneumatic mounted opposite the projection on the lever but normally out of contact with the same, said pneumatic being arranged so that when expanded its swinging 55 leaf will strike the end of said projection.

2. The combination of a power pneumatic having one of its sides provided with air and suction ports, a lever extended from one of said ports to the other and pivoted 60 between the same, the ends of said lever serving as valves for said ports, and pneumatic means controlling said lever, said lever being arranged inside of said pneumatic and extended along said wall, and 65 said pneumatic means being outside of said

pneumatic, a wind chest in which said pneumatic means is located, and a prong on one end of said lever extending through said suction port and coöperating with said pneumatic means, said prong being normally out 70 of contact with said pneumatic means but arranged to be struck upon the operation of the same.

3. The combination of a power pneumatic having one of its sides provided with air 75 and suction ports, a lever extended from one of said ports to the other and pivoted between the same, the ends of said lever serving as valves for said ports, and pneumatic means controlling said lever and act- 80 ing upon one end of the same, the opposite end of said lever being weighted, said pneumatic means being normally out of contact with and separated from said lever and arranged to strike the same when actuated. 85

4. The combination of a power pneumatic having one of its side walls provided with air and suction ports, a lever extending lengthwise of said side wall between said ports and pivoted near its middle, the ends 90 of said lever being adapted to serve as valves for said ports, a wind chest at one end of said pneumatic, said wind chest having a wind chamber communicating by said suction port with the interior of said pneumatic, 95 a small pneumatic located in said wind chamber, and a projection on said lever extending through said suction port and in position to contact with said small pneumatic, but normally out of contact with and separated 100 from the same.

5. The combination of a power pneumatic having one of its side walls provided with air and suction ports, a lever extending lengthwise of said side wall between said 105 ports and pivoted near its middle, the ends of said lever being adapted to serve as valves for said ports, a wind chest at one end of said pneumatic, said wind chest having a wind chamber communicating by said suction port with the interior of said pneumatic, a small pneumatic located in said wind chamber, a projection on said lever extending through said suction port and in position to contact with said small pneumatic, but normally out of contact with and separated from the same, and a tracker board tube attached to said wind chest and communicating with said small pneumatic. 110

6. The combination of a power pneumatic 115 having one of its side walls provided with air and suction ports, a lever extending lengthwise of said side wall between said ports and pivoted near its middle, the ends of said lever being adapted to serve as valves for said ports, a wind chest at one end of said pneumatic, said wind chest having a wind chamber communicating by said suction port with the interior of said pneumatic, a small pneumatic located in said 120

wind chamber, a projection on said lever extending through said suction port and in position to contact with said small pneumatic, but normally out of contact with and separated from the same, and a tracker board tube attached to said wind chest and communicating with said small pneumatic, the side wall along which said lever extends

being provided with a groove to accommodate said lever, and the latter being pivoted 10 by an adjusting screw.

In witness whereof I hereunto subscribe my name this 2nd day of August, A. D. 1919.

ADOLPH P. GUSTAFSON.
